US00D939274S

(12) **United States Design Patent** (10) Patent No.: **US D939,274 S**
McConnell et al. (45) Date of Patent: **** Dec. 28, 2021**

- (54) **GRINDER PLATE AND CLEANER
ACCESSORY ASSEMBLY**
- (71) Applicant: **WHIRLPOOL CORPORATION**,
Benton Harbor, MI (US)
- (72) Inventors: **John W. McConnell**, St. Joseph, MI
(US); **Nicholas Schutte**, St. Joseph, MI
(US); **Anne Wessel**, St. Joseph, MI
(US)
- (73) Assignee: **Whirlpool Corporation**, Benton
Harbor, MI (US)
- (**) Term: **15 Years**
- (21) Appl. No.: **29/798,469**
- (22) Filed: **Jul. 8, 2021**
